DISPENSING HEAD ASSEMBLY FOR A FLUID DISPENSING SYSTEM

Warren E. Turner, Succasunna, N.J., assignor to H. H. Thermostats, Inc., Cedar Grove, N.J., a corporation of New Jersey

Filed Mar. 18, 1969, Ser. No. 16,313

Term of patent 14 years

Int. Cl. D23—01

U.S. Cl. D67—4

FIG. 1

FIG. 2

FIG. 3

FIG. 4

FIG. 1 is a side elevational view of the dispensing head assembly showing my new design;

FIG. 2 is a front elevational view of the dispensing head assembly of FIGURE 1;

FIG. 3 is a top elevational view of the dispensing head assembly of FIGURE 1, and

FIG. 4 is a perspective view of the dispensing head assembly of FIGURE 1.

I claim:

The ornamental design for a dispensing head assembly for a fluid dispensing system, as shown and described.
